REARVIEW MIRROR

Kenneth J. Fischer, 3248 Fruitwood Lane,
Jacksonville, Fla. 32211

Filed May 4, 1971, Ser. No. 140,314

Term of patent 14 years

Int. Cl. D12—08

U.S. Cl. D14—6 M

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a front view of the reflective faces of a rearview mirror adapted to be mounted on the left hand side of a truck in accord with an embodiment of my new design;

FIG. 2 is a side elevation view thereof;

FIG. 3 is a back view showing the non-reflective faces thereof;

FIG. 4 is a cross-sectional view taken along line 4-4 of FIG. 1;

FIG. 5 is a cross sectional view taken along line 5-5 of FIG. 1;

FIG. 6 is a bottom end elevational view taken along line 6-6 of FIG. 2;

FIG. 7 is a front view of the reflective faces of a rearview mirror adapted to be mounted on the right hand side of a truck in accord with another embodiment of my new design;

FIG. 8 is a side elevational view thereof;

FIG. 9 is a back view showing the non-reflective faces thereof;

FIG. 10 is a cross sectional view taken along line 10-10 of FIG. 7;

FIG. 11 is a cross sectional view taken along line 11-11 of FIG. 7; and

FIG. 12 is a top end elevational view taken along line 12-12 of FIG. 8.

I claim:

The ornamental design for a rearview mirror, substantially as shown and described.
